WIRE TERMINAL

Donald Matt Weiger, Seattle, Wash., assignor to
The Trumbull Electric Manufacturing Company, Plainville, Conn., a corporation of Connecticut

Application June 18, 1938, Serial No. 214,494

5 Claims. (Cl. 173—259)

This invention relates particularly to an improved wire terminal construction.

It is desired that a conductor wire to be connected to the shank of a screw or binding post be looped around the shank or post in order to retain the same securely in position on the shank and to provide a positive contact.

A special object of my invention is to provide a wire looping device which is adapted to be so associated with a wire fastening member such as a slotted screw that the same movement of the tool for tightening the screw also simultaneously loops and clamps the wire securely.

Another object is to provide a wire looping device that is simple in construction and reliable in operation.

Another object is to provide such a wire looping device that may be used with the ordinary commercial forms of binding posts.

20 In carrying out my invention, I provide a washer member positioned between the seat of a terminal and the slotted head of a fastening screw. A lug is formed on the periphery of the washer and extends adjacent the periphery of the screw head so that a tool inserted into the slot in the screw head is adapted to engage the lug and turn the same along with the screw head and so that the free end of a wire beneath the screw head will be engaged by and carried 25 around with the lug and formed into a loop.

In the drawing,

Figure 1 is a plan view of a fuse unit embodying my improved wire terminal construction.

Figure 2 is an end view thereof.

35 Figure 3 is a sectional view showing the improved wire terminal partly in section and partly in elevation.

Figure 4 is a detail view of my improved wire terminal showing a conductor wire, looping washer and tool in initial wire looping position.

40 Figure 5 is a detail view showing the wire partly looped.

Figure 6 is a spread perspective view of my improved wire terminal.

45 In the drawing, I have shown a commercial form of fuse unit with a body formed of insulating material and having an ordinary terminal member 7 fastened to one of the contacts of a socket shell as is customary. Seated on the free end of the terminal 7 is a washer member 8 and a screw 9. The terminal 7 has a screw threaded opening 10 and the threaded shank 11 of the screw passes freely through the opening 12 of the washer. Terminal 7 is preferably formed with an upturned lug 13. The washer 8 has a lug 14

which extends slightly outward of the periphery of the washer and at right angles to the plane of the body of the washer to engage the end 15 of the conductor wire or wires. When washer 8 is seated on terminal 7, lug 14 is positioned sufficiently remote from the shank and head of the screw 9 to permit turning thereof but sufficiently close to the head of the screw to be in the path of the turning movement of the tip edge of a screw driver or tool 16 inserted in the slot 17 of the 10 screw so that a turning movement will be imparted to said washer and its lug 14.

The bared end of a conductor wire 15 to be fastened is placed between the head of the screw 9 and the body of washer 8 to the right of lug 18 20 of washer 8 as viewed in Fig. 4. The tip edge of the tool 16 is placed in the slot 17 of screw head 9 with its opposite edge extending beyond the periphery of the head of the screw so as to engage lug 14 of washer 8 during its turning movement and carry the lug around. In its turning movement lug 14 engages the free end of conductor wire 15 and bends it around the shank 11 of the screw as shown in Fig. 5. Further turning of the tool will cause the lug 14 to form 25 a loop as shown in Figs. 1 and 2, the lug 13 on terminal 7 and the shank of the screw serving to cramp the wire therebetween to prevent further lengthwise movement of the wire. As soon as the loop in the wire has been formed, the screw 30 driver may be released from its engagement with the lug 14 on washer 8 and then manipulated to turn the screw 9 to secure the wire in position.

It will be understood that the turning of the screw clamps the looped wire positively between 35 the screw head and body of the washer 8.

It will also be understood that the improved washer for looping wire may be used on any sort of a terminal having a single wire retaining lug or having any kind of an adjacent shoulder 40 which may function as a wire-retaining lug.

The screw may be staked at its lower end to prevent its loss by dropping out.

I claim:

1. A binding post construction embodying a 45 terminal member having a screw threaded seat, a screw member having a slotted head and a threaded shank rotatable in the threaded slot of the terminal member, and a bending member freely rotatable on said shank and having a 50 clamping portion adjacent the threaded seat and having an upstanding projection extending alongside of the head of the screw member beyond the plane of the slot therein and adapted to be engaged by the edge of the blade of a screw

driver when the screw driver tip is engaged in the slot of the head of the screw member so that the bending member can be rotated by the screw driver and thereby bend the tip of a wire inserted between the clamping portion of the bending member and the head of the screw member.

5. A binding post construction including a terminal member having a screw threaded opening, a screw having a slotted head portion and a shank portion in said opening, a washer member rotatably mounted on said shank between said head portion and terminal, and a lug on said washer extending outwardly beyond the slot in the head in the path of movement of a turning tool in the slot of said head portion whereby said movement is imparted to said lug and whereby the free end of a wire placed between the shank of the screw and the lug is carried 10 therearound.

20. 3. A binding post construction including a terminal member having a screw threaded opening, a screw having a slotted head portion and a shank portion in said opening, a washer member 25 rotatably mounted on said shank portion between said head and terminal, a lug on said washer extending outwardly beyond the slot in the head in the path of movement of a turning tool in the slot of said head portion whereby said 30 movement is imparted to said lug and whereby the free end of a wire placed between the shank

of the screw and the lug is carried therearound, and a lug on said terminal adapted to coat with said screw head portion for binding the wire therebetween.

4. A binding post construction including a terminal member having a seat portion with a threaded opening, a washer freely rotatable on said seat portion, a screw member with a slotted head portion and a shank portion movable through the threaded opening of said seat portion and a lug on the periphery of said washer extending beyond the slot in the head and positioned sufficiently close to the head of the screw to be engaged by a tool used to turn said screw head whereby said lug is adapted to be carried around with said screw head and carry the free end of a wire placed between said lug and shank of the screw around with it to form a loop in 15 said wire, 15

5. In a binding post construction, a terminal 20 having a screw threaded opening, a screw having a slotted head and a shank portion movable in said opening, a washer member freely rotatable on said shank between said head and terminal, and a lug on said washer extending beyond the slot in the head and positioned in the path of movement of a tool to be engaged in the slot of said head for looping a wire around said shank. 25

DONALD MATT WEIGER.
